UNITED STATES PATENT OFFICE

114,651

DESIGN FOR A RADIO CABINET

George W. Walker, Pleasant Ridge, Mich., assignor to Detrola Corporation, Detroit, Mich., a corporation of Michigan

Application March 29, 1938, Serial No. 76,157

Term of patent 3½ years

To all whom it may concern:

Be it known that I, George W. Walker, a citizen of the United States and a resident of Pleasant Ridge, Mich., in the county of Oakland and State of Michigan, have invented a new, original, and ornamental Design for Radio Cabinet, of which the following is a specification, reference being had to the accompanying drawing, forming part thereof, in which

Figure 1 is a front elevation of a radio cabinet showing my new design; and

Figure 2 is a side elevation thereof as seen from the left of Figure 1.

The dominant features of my design reside in the portions shown in solid lines in the drawing.

I claim:

The ornamental design for a radio cabinet, substantially as shown and described.

GEORGE W. WALKER.
